UNITED STATES PATENT OFFICE.

HARRY H. IDE, OF LA GRANGE, ILLINOIS, ASSIGNOR TO KELLOGG SWITCHBOARD AND SUPPLY COMPANY, OF CHICAGO, ILLINOIS, A CORPORATION OF ILLINOIS.

TELEPHONE SYSTEM.

1,381,195.

Specification of Letters Patent. Patented June 14, 1921.

Application filed May 15, 1919. Serial No. 297,244.

To all whom it may concern:

Be it known that I, HARRY H. IDE, a citizen of the United States of America, residing at La Grange, in the county of Cook and State of Illinois, have invented certain new and useful Improvements in Telephone Systems, of which the following is a specification.

My invention relates to telephone systems and has to do more particularly with systems of the type in which impulses transmitted from a calling substation actuate switches to seek the contacts of the line being called. The system which is herein disclosed is particularly applicable to private branch exchange systems and is commonly known in the art as a private automatic exchange, although my invention is in no sense limited to such use. The system is adapted to serve a plurality of stations, say twenty-five in number, each station of the system being supplied with a single motion rotary switch.

A system of the type above described does away with the usual operator used in manual private branch systems, and an object of my invention is the provision of an improved circuit arrangement which embodies desirable features and advantages all in an efficient, simple and economical manner.

The novel features of the invention through the provision of which the above-mentioned and other advantageous results are attained will be explained by reference to the accompanying drawings, in which like reference characters in the several views denote like parts and in which—

Figure 1 is a plan view of a switch adapted to operate in connection with the circuit arrangement;

Fig. 2 is a front elevation of the switch;

Fig. 3 is a right side elevation of the switch;

Fig. 4 is a sectional view of the main shaft showing its constructions, and

Fig. 5 illustrates diagrammatically a system including the circuit of my invention.

Referring now more particularly to the switch structure illustrated in Figs. 1 to 4, inclusive, the switch comprises a mounting plate 2 to which are secured the operating parts of the switch and also the bank of con-

tacts B. The switch as illustrated in Figs. 1 to 4 is similar to the type of switch illustrated and described in my application, Serial No. 271,960, filed January 20, 1919.

The bank contacts B coöperate with the wipers W, which latter are supported upon a shaft S. Plate 2 further supports a motor magnet MM, a combined line and inter-rupter relay LR, a switching relay SW and a ringing relay RI.

Contact bank B comprises any suitable number of contact sets, each set including a private contact 4, a common contact 5 and line contacts 6 and 7. Twenty-five sets of contacts 4, 5, 6 and 7 per switch is a convenient number. The contacts are radially disposed between the clamping plates 8 and 9 and are properly spaced and insulated from each other. Bolts 10 and nuts 11 form the clamping means to secure the contact bank B, as a whole, between the plates 8 and 9.

To secure the bank of contacts to the supporting posts 3 (which are securely fastened to the plate 2), I provide the lower plate 9 with ears 12 and 13 bent over parallel to the plane of the said plate. Ears 12 and 13 and plates 8 and 9 have openings to receive posts 3. The bank B, as a whole, is slipped over the posts 3, and screws 14 which have screw-threaded engagement with the bridge portion of the ears 12 and 13 are tightened to maintain the bank B, as a whole, in its adjusted position.

Wipers 15, 16, 17 and 18, which coöperate with the contacts 4, 5, 6 and 7 comprise two oppositely extending arms each and the bank contact B, as a whole, forms a semi-circle so that when one set of wiper arms leaves the last contact set, the other set of wiper arms engages the first contact set. The wipers 15, 16, 17 and 18 are carried by a hub 19, which is slipped over the shaft S and when the wipers are adjusted in relation with the contact banks, a set screw 20 is tightened to hold the wiper unit W upon the shaft S. The wipers 15, 16, 17 and 18 are conductively connected to conducting rings 21, 22, 23 and 24, respectively, which are also suitably mounted upon the hub 19 but insulated therefrom, as are also the wipers. Conducting rings 21, 22, 23 and 24 form contacting

surfaces for wiper brushes 25, 26, 27 and 28, insulatingly mounted upon a stud 29 and clamped by means of the nut 30, the stud 29, as a whole, being then secured to the plate 5 2 by means of the screw 31. The brush wipers 25, 26, 27 and 28 contact respectively and permanently with the conducting rings 21, 22, 23 and 24, and since the rings are as stated conductively connected to wipers 15, 10 16, 17 and 18, wipers 15, 16, 17 and 18 are always conductively connected to terminals 25', 26', 27' and 28'.

Sleeve 32 supported by plate 2 serves as a bearing for the shaft S and also as a bearing 15 for the ratchet 33 which operates to rotate the shaft S and the wiper unit W over the bank contacts. The sleeve 32 has its one end 32' threaded and its other end provided with a flanged portion 32², the said flanged 20 portion 32² resting in a recess 34 in the ratchet 33. A collar 35 has screw-threaded engagement with the threaded portion 32' of the sleeve 32 and its peripheral surface also forming a bearing for the ratchet 33. 25 The collar 35 is provided with a reduced portion 36 which fits into a suitable orifice 37 in the plate 2. I provide a nut 38 which has screw-threaded engagement with the threaded portion 32' of the sleeve 32 and when the 30 proper adjustment of the ratchet 33 and parts is obtained, the nut 38 is tightened to secure the sleeve 32 and its supported parts in their adjusted position. A plate 39 is secured to the ratchet 33 by means of the 35 screws 40 and 41, and is provided with an angular extension 42 for purposes as will presently be described. The shaft S is provided with a squared portion 43 at its upper end which enters a square opening 44 in the plate 39. A suitable screw 45 passing 40 through a suitable opening in the plate 39 has screw-threaded engagement with a suitable tapped orifice in the squared end 43 of the shaft S, thus connecting the shaft S to 45 the plate 39 so that when the ratchet 33 is rotated, as will presently be described, the shaft S is also rotated therewith.

The motor magnet MM, which is adapted 50 to move the wipers over bank contacts, includes a pole piece 46, an armature 47, and a driving pawl 48. The electromagnet 49 is suitably secured to the pole piece 46 by means of a screw 50 which passes through a stud 51, the said screw having screw-threaded engagement with a suitable tapped opening 55 in the core 52 of the magnet 49.

The pole piece 46 has projecting ears 53 bent at right angles to the main part of the said pole piece, the said ears having suitable 60 tapped orifices which receive screws 54 to fasten the magnet 49, pole piece 46 and armature 47 as a unit to the mounting plate 2. The pole piece 46 is provided with projecting ears 55, bent at right angles to the 65 main part of the pole piece, the said ears

having suitable openings to receive the pivot pin 56, which pivot pin 56 pivotally supports the armature 47 of the motor magnet MM. The armature 47 is also provided with ears 57 which have suitable openings to 70 receive the said pivot pin 56. A U-shaped member 58 is also provided, the arms of which also have suitable openings for receiving the pivot pin 56. To pivotally support the armature 47 upon the pole piece 46, 75 the pivot pin 56 is inserted through the openings in the ears 55 of the pole piece 46 and the ears 57 of the armature 47, and through the openings in the arms of the U-shaped member 58. One arm of the member 58 80 fits between one of the supporting ears 55 of the pole piece 46 and the adjacent ears 57 of the armature 47. A set screw 60 is provided and has screw-threaded engagement with the yoke end of the U-shaped member 85 58. The set screw 60 is used to securely hold the pivot pin 56 in place relative to the heel iron 46 and armature 47.

The armature 47 carries a pivoted driving pawl 48 which is normally held against an 90 adjustable stop 62 by means of a leaf spring 63, the said leaf spring 63 being held in place by means of a screw 64. The adjustable stop 62 is pivotally secured to the mounting plate 2 by means of a screw 65. 95 The stop 62 has an enlarged end 62' provided with a slot 66, through which a screw 67 passes. To adjust the pawl 48, the screws 65 and 67 are loosened and the stop 62 is then moved about its pivot screw 65, causing the angular portion 62² to move to the right or left, as the case may be, and when the proper adjustment is obtained, the screws 65 and 67 which have screw-threaded engagement with suitable tapped openings in 100 the plate 2, are tightened to hold it in its adjusted position. The armature 47 is held in its normal position by means of a coil spring 68, the said spring having its one end fastened to a pin 69 which is staked to the pole piece 46, and its other end is secured to an adjustable screw 70. The screw 70 passes through a suitable opening in the arm 71, which arm 71 is integrally formed with the armature 47, the said screw 70 115 being provided with an adjustable nut 72. The tension of the spring 68 is regulated by means of the nut 72. A set of contact springs J is associated with the motor magnet MM, the said springs being insulatingly 120 mounted upon the pole piece 46 by means of the screws 73, which are suitably insulated from the springs J.

The pawl 48 is adapted to engage a tooth of the ratchet wheel 33 upon each actuation 125 of the motor magnet MM, and an adjustable stop post 74 is provided to limit the stroke of the pawl 48 so that the wipers 15, 16, 17 and 18 are only advanced one step at a time. The stop post 74 has a reduced por- 130

tion which passes through a suitable slot 75 in the plate 2. The stop 74 may be moved forward or backward as the case may be, and when the desired adjustment is obtained 5 suitable means are tightened to securely hold the stop 74 in its adjusted position.

The line relay LR, ringing relay RI and the switching relay SW are suitably mounted upon a bracket 76, which bracket is in 10 turn secured to the mounting plate 2 by means of the screws 77. The relays LR, RI and SW are similarly constructed and comprise the usual electromagnet 78, heel iron 79 and pivoted armature 180. Nuts 15 181, having screw-threaded engagement with threaded portions of the core of the electromagnets, secure them to the bracket 76.

A set of off-normal contacts ON are insulatingly mounted upon a bracket 182 by 20 means of the screws 183, and are held in their normal position by means of the angular extension arm 42 of the plate 39 in the form of an arm 42. The arm 42 when the switch is at normal engages a rubber buffer 283 to hold the said off-normal contacts ON in their normal position. Upon the first 25 step of the switch wipers off normal, the arm 42 disengages the buffer 283 allowing the contacts ON to assume their alternate position and remain in such position until the arm 42 again engages the buffer 283 which occurs when the switch has completed a revolution. The bracket 182 is suitably secured to the mounting plate 2 by means of 30 the screws 184. A condenser K is mounted upon the plate 2 by means of a bracket 185 secured to the plate 2 by means of the screw 35 186.

The circuit in Fig. 5 shows a calling sub- 40 station A connected to the switch circuit D of my invention and adapted to operate with the switch structure just described. The calling substation A comprises the usual substation apparatus and in addition comprises 45 a calling device CD and a grounding or ringing key GK for purposes as will presently be described, and the called line C is similarly equipped.

Assuming now that the subscriber at the 50 calling substation A initiates a call, he removes his receiver, thus closing a circuit for the line relay LR and ringing relay RI, traced from battery through the winding of relay LR, conductor 80, through the sub- 55 station, conductor 81 to ground through the winding of ringing relay RI. The two relays LR and RI are thus energized in series. Assuming further that it is the subscriber at substation C that is wanted and 60 his number is 15, the subscriber at substation A now actuates his calling device to send fifteen impulses of current over the line by first sending ten impulses and then five, as is well understood, or any other combination 65 of impulses to make the requisite number.

The impulses bring about fifteen rapid de-energizations and energizations of the line relay LR. The ringing relay RI does not deenergize during the rapid interruptions of current, as it is a slow-acting relay of usual 70 construction. Upon the first deenergization of relay LR, an energizing circuit for motor magnet MM is established, traced from battery, through the winding of motor magnet MM, conductor 82, normal contact 83 of 75 relay LR, conductor 84, normal contact 85 of switching relay SW, conductor 86, to ground at alternate contact 87 of ringing relay RI. The magnet MM upon energization causes the pawl 48 to engage a tooth of 80 the ratchet 33, stepping the wipers 15, 17 and 18 into engagement with the first set of contacts 4, 6 and 7, and the motor magnet MM is energized and deenergized fifteen 85 times due to the closing and opening of normal contact 83, and the wipers 15, 17 and 18 are stepped into engagement with the fifteenth set of contacts 4, 6 and 7 which are the contacts of the called substation C. Upon the first step of the wipers off normal, 90 off-normal contacts ON assume their alternate positions and the closing of alternate contact 88 places a ground or busy potential upon the private normals 89 of the calling substation A, making it busy against any incoming calls.

After the subscriber at the calling substation A has sent the impulses, he depresses the key GK to impress ringing current upon the called subscriber's line, and relay LR remains energized while relay RI is short circuited and falls back. Assuming that the called line is idle, the depression of the key GK brings about a series energizing circuit for the switch relay SW and the switch relay 100 SW' of the individual switch D' of the called line C, traced from battery through the lower winding of relay SW', conductor 90, normal contact 91 of primary off-normal contacts ON', conductor 92, normal contact 105 93 of relay LR', conductor 94, normal contact 95 of relay RI', conductor 96, contact 4, wiper 15, conductor 97, upper winding of relay SW, conductor 98, alternate contact 99 of relay LR, normal contact 100 of relay 110 RI (the said relay RI restoring when the key GK is depressed as it is shunted, the said shunt being traced from ground at alternate contact of the key GK, conductor 81 to ground through the winding of relay 115 RI), conductor 101, conductor 102, to ground at alternate contact 88 of primary off-normal contacts ON. The closing of alternate contact 111 of switching relay SW closes a locking circuit for itself, traced 120 from battery, through the lower winding of relay SW, alternate contact 111, conductor 86, to ground at alternate contact 87 of relay RI. Upon each actuation of the key GK, 125 relay RI restores for reasons as already de- 130

scribed, and the opening of alternate contact 87 opens the circuit of relay SW, but an alternative circuit for relay SW is closed during the de-energization of relay RI, 5 traced from battery, through the lower winding of relay SW, alternate contact 111, conductor 86, conductor 103, alternate contact 104 of relay LR, conductors 105 and 102 to ground at alternate contact 88 of off- 10 normal contacts ON. Each depression of the key GK impresses ringing current upon the called line, due to the de-energization of relay RI upon each actuation of key GK, the ringing circuit being traced from the 15 ungrounded pole of the generator G, alternate contact 106 of relay SW, conductor 107, normal contact 130 of relay RI, alternate contact 109 of relay SW, wiper 18, conductor 7, through the call bell and condenser of the 20 called substation C, back through contact 6, wiper 17, alternate contact 110 of relay SW, conductor 81, through relay RI to ground. The closing of alternate contact 112 of relay SW places a ground or busy 25 potential upon the private contact 4 from ground at alternate contact 88 of off-normal contacts ON, conductors 102 and 105, alternate contact 104 of relay LR, conductors 103 and 86, alternate contact 112 of relay SW, 30 conductor 97, wiper 15 to contact 4, thus preventing any other calling subscriber from engaging with the contacts of the 35 called line.

When the called subscriber at the substation C answers in response to his call bell, 35 the removal of the receiver thereat closes an energizing circuit for the line relay LR' and the ringing relay RI' of the switch D' associated with the called line, from battery, through the winding of relay LR', conductor 113, through the now closed contacts of the substation switch hook, conductor 114 to ground through the winding of relay RI'. The closing of alternate contact 115 40 of relay RI' closes a locking circuit for the switching relay SW' from battery through its alternate contact 116, conductor 117 to ground at alternate contact 115 of relay RI'. The subscribers at substations A and C are 45 now in conversational circuit, and the talking circuit may be traced over the heavily marked conductors, the said conductors having the condensers K and K' interposed.

Assuming now that the subscribers at 50 stations A and C have finished conversation, the calling subscriber A replacing his receiver upon the switch hook allows the relays RI and LR to restore, due to the opening of the switch hook contacts, and the 55 opening of contact 87 of relay RI opens the locking circuit of switching relay SW, which relay restores to normal. The closing of normal contact 99 of relay LR and normal contact 100 of relay RI establishes 60 an energizing circuit for motor magnet MM,

traced from battery, through the winding of magnet MM, its normal contact 120, conductor 121, alternate contact 122 of off-normal contacts ON, conductor 123, normal contacts 99 and 100, conductors 101 and 102 to ground at alternate contact 88 of off-normal contacts ON. The magnet MM upon energization causes the wipers 15, 17 and 18 to be stepped from the contacts it was engaging and the opening of its contact 120 70 opens the circuit of the magnet MM, allowing it to restore, and the closing of its contact 120 again energizes the magnet MM. The magnet MM is thus energized and de-energized, stepping the wipers 15, 17 and 18 75 until the arm 42 again engages the off-normal contacts ON, moving them back to their normal position, and the opening of contacts 88 and 122 of the said off-normal contacts ON opens the energizing circuit 80 of magnet MM preventing further movement of the switch wipers 15, 17 and 18. The replacing of the receiver at the called substation C opens the energizing circuit 85 for relay RI' and LR' at the switch hook 90 contacts, and relay RI' restoring opens its alternate contact 115, allowing the switching relay SW' to restore provided the calling subscriber has already hung up, which places the apparatus of the switch D', associated with the called subscriber, at normal. The apparatus used in establishing the above described connection is now at 95 normal and is available for use in establishing other connections.

Assuming now that the called line is busy, the operation of the circuit is the same as previously described up to the time that the calling subscriber depresses the key GK. If the wanted line is busy as a calling line, 105 its private normals 4 will be grounded from the alternate contact 126 of the off-normal contacts ON', while if busy, as a called line, its private normals will be grounded, from the ground extending through the alternate 110 contact of the switching relay SW of the switch of the calling line, as already described. The calling subscriber having selected the contacts of the called line, now depresses the key GK. A path extends 115 from ground at the busy contact 4, wiper 15 of switch D, conductor 97, through the upper winding of relay SW, conductor 98, alternate contact 99 of relay LR, normal contact 100 of relay RI, (the said relay being short circuited upon the depression of the key GK, as already described), conductors 101 and 102 to ground at alternate contact 88 of off-normal contacts ON. Relay SW does not energize in this instance, due 120 to its upper winding being grounded at both ends, and a busy signal is transmitted to the calling subscriber, traced from the busy signal BB, normal contact 109 of relay SW, alternate contact 130 of relay RI 125 130

(the said relay RI again energizing as soon as the key GK is released), through the receiver of the calling subscriber at substation A, back over conductor 81 and through 5 the winding of relay RI to ground. The calling subscriber receiving the busy signal, now replaces his receiver and this act opens the circuit for relays RI and LR, bringing about the energization of the motor magnet 10 MM, which magnet MM steps the wipers ahead as previously described, until they reach normal, when the switch is again available for establishing other connections.

In describing my invention I have employed preferred circuit arrangements, but it is to be understood that various changes may readily suggest themselves to those skilled in the art, and I, therefore, do not desire to be limited to the exact arrangement shown and described, but aim to cover all such changes and modifications which come within the spirit and scope of the appended claims.

What I claim as new and desire to secure 25 by United States Letters Patent, is:

1. A telephone system including a subscriber's line, an automatic adding-type connector switch individual to said subscriber's line controlled over the two sides 30 of the subscriber's line in series, a single row or level of bank contacts for said automatic switch, other subscribers' lines terminating in said bank contacts, subscriber-controlled means for said switch for connecting said first subscriber's line to any one of said other subscribers' lines, subscriber-controlled means for ringing the called substation, and automatic means for moving said switch to normal position.

40 2. A telephone system including a subscriber's telephone line, an automatic adding-type connector switch individual thereto and controlled over the two sides of the subscriber's line in series, bank contacts for said switch, subscribers' lines terminating in said bank contacts, step-by-step means for said switch for connecting said first subscriber's line to any of said other subscribers' lines, subscriber-controlled means for ringing 45 the called substation, and automatic means for operating said step-by-step means to move the wipers of said switch to a normal position.

3. A telephone system including a subscriber's telephone line, an automatic switch individual thereto, a pair of line relays for said switch connected to said subscriber's line, a single level of bank contacts for said switch, other subscribers' lines connected to 50 said bank contacts, an impulse sending device for operating one only of said line relays to cause a connection to be established between said first subscriber's line and one of said other subscribers' lines, and subscriber-controlled means for maintaining 55

said line relay energized and for deenergizing the said other line relay to signal the called subscriber.

4. A telephone system including a subscriber's telephone line, an automatic switch 70 individual thereto, a pair of line relays for said switch connected to said subscriber's line, a single level of bank contacts for said switch, other subscribers' lines connected to said bank contacts, an impulse sending device for operating one of said line relays to cause a connection to be established between 75 said first subscriber's line and one of said other subscribers' lines, subscriber-controlled means for maintaining said line relay energized and for deenergizing the said other line relay to signal the called subscriber, and subscriber-controlled means for deenergizing 80 both of said line relays, whereby said switch resumes a normal position.

5. A telephone system including a subscriber's telephone line, an automatic switch individual thereto, a pair of line relays for said switch connected to said subscriber's line, a single level of bank contacts for said 90 switch, other subscribers' lines connected to said bank contacts, an impulse sending device for operating one of said line relays to cause a connection to be established between said first subscriber's line and one of said 95 other subscribers' lines, subscriber-controlled means for maintaining said line relay energized and for deenergizing the said other line relay to signal the called subscriber, and automatic means for said switch, controllable by the deenergization of both the 100 said line relays for advancing the wipers of said switch to normal position.

6. A connector circuit including a telephone line, a pair of electro-magnets in series 105 therewith; means for vibrating the first by digit impulses, while the second maintains its armature in operated position; circuit connections for holding the first in operated position while the second retracts its armature; a test relay switched into circuit by 110 said magnets; a source of ringing current connected in when said relay is in one operative position; a source of busy current connected in when said relay is in another 115 operative condition.

7. A connector circuit including a telephone line, a pair of electro-magnets in series therewith; means for vibrating the first by digit impulses, while the second 120 maintains its armature in operated position; circuit connections for holding the first in operated position while the second retracts its armature; a test relay switched into circuit by 125 said magnets; a called line; a test relay for said line in circuit with said first relay; a source of current connected to said circuit and energizing both said relays when the called line is idle.

8. A calling and a called telephone line; 130

a connector for each line, said connectors having each a test relay in temporary circuit with each other; and calling line means for connecting a current source to said circuit.

9. A connector having a quick and a slow electro-magnet, the first retracting and the other holding its armature responsive to substation control; substation means to reverse said positions of said armatures; travel controlling means sensitive to the first armature relation; and test controlling means sensitive to the second armature relation.

10. A telephone system including a calling and a called line, each having a connector, said connectors temporarily switched together; a test relay for each connector adapted to operate in circuit with one another 10 when the called line is idle; and an off normal contact of each connector controlling a circuit of its relay.

11. A telephone system including a calling and a called line, each having a connector, said connectors temporarily switched together; a test relay for each connector adapted to operate in circuit with one another when the called line is idle; and two off normal contacts of each connector controlling the circuit of its relay.

12. A telephone system including telephone lines; a connector, an off normal contact serving to place a busy potential on the private normal of said connector; means for connecting said contact to a wiper of said connector to test the called line; a test relay with a winding in series between said contact and said wiper, and operating in a manner dependent on the electrical condition of 40 an engaged called line contact for switching a connection to said wiper to render the called line busy.

13. A connector for automatic exchanges including a relay adapted to be operated in series with the two limbs of a line or over one limb thereof; a called line; and a test relay for said connector to test the called line having a test winding controlled by said first relay and a locking winding for 50 said test relay.

14. A connector for automatic exchanges including a relay adapted to be operated over the two limbs of the line or over one limb at the will of the subscriber; a test relay for said connector, circuit means controlled by said first relay for controlling said test relay; and an off normal contact in the circuit of said test relay.

15. A connector for automatic exchanges including a relay adapted to be operated over the two limbs of the line or over one limb at the will of the subscriber; a test relay for said connector, circuit means controlled by said first relay for controlling 65 said test relay; and two off normal contacts

for said connector and a circuit connection from each contact to said test relay.

16. A connector for automatic exchanges including a relay adapted to be operated over the two limbs of the line or over one limb at the will of the subscriber; a test relay for said connector, circuit means controlled by said first relay for controlling said test relay; means for switching said test relay to operatively connect with the 75 called line, an off normal contact controlled from the calling line, another controlled from the called line, the circuits of said test relay being connected to both said contacts.

17. A connector for automatic exchanges including a relay adapted to be operated over the two limbs of the line or over one limb at the will of the subscriber; a test relay for said connector, circuit means controlled by said first relay for controlling said test 85 relay; means for switching said test relay to connect with the called line, an off normal contact controlled from the calling line, another controlled from the called line, the circuits of said test relay being connected to both said contacts; and a talking circuit 90 of said connector including normally open contacts of said test relay.

18. A connector for automatic exchanges including a relay adapted to be operated over the two limbs of the line or over one limb at the will of the subscriber; a test relay for said connector, circuit means controlled by said first relay for controlling said test relay; an off normal contact in the 100 circuit of said test relay; and ringing and busy back connections controlled by said test relay.

19. A connector for automatic exchanges including a relay adapted to be operated over the two limbs of the line or over one limb at the will of the subscriber; a test relay for said connector, circuit means controlled by said first relay for controlling said test relay; an off normal contact in the circuit 105 of said test relay; a talking circuit of said connector including normally open contacts of said test relay; ringing and busy back connections controlled by said test relays.

20. A connector for automatic exchanges including a relay adapted to be operated over the two limbs of the line or over one limb at the will of the subscriber; a test relay for said connector, circuit means controlled by said first relay for controlling said 110 test relay; a slow release relay for said connector subject to substation control, said test relay when energizing locking first over a contact of said first mentioned relay and then over a contact of said slow relay.

125
21. A connector for automatic exchanges including a relay adapted to be operated over the two limbs of the line or over one limb at the will of the subscriber; a test relay for said connector, circuit means con- 130

- trolled by said first relay for controlling said test relay; a slow relay for said connector subject to substation control, said slow relay also controlling said test relay; 5 a called line and a relay therefor, means for energizing said test relay and said called line relay in series, said relays locking over a contact of said first mentioned relay and also over an independent locking circuit including a contact of said slow relay.
22. A connector for automatic exchanges, including a test relay, a slow relay subject to substation control and serving to operatively connect said test relay, a third relay, 15 a locking circuit for said test relay, including a switch contact of said third relay, another locking circuit for said test relay including a contact of said slow relay and means for successively closing said locking 20 circuits.
23. A connector including a test relay, an energizing circuit and two holding circuits for said relay, and switch means for closing said three circuits in succession.
24. A connector including a relay, line 25
- switching contacts on said relay, an energizing circuit and a locking circuit for said relay, and holding means to retain said relay in operated position after the establishment of said energizing circuit and until said locking circuit is completed. 30
25. An automatic telephone system including a pair of telephone lines connected to connectors respectively, said lines temporarily switched together, a test relay for 35 each connector, and means for energizing both said test relays when the called line is tested.
26. An automatic telephone system including a pair of telephone lines provided 40 with individual adding-type connectors, respectively, said lines being temporarily switched together, a relay for each connector, and means for energizing both of said relays when a connection is effected. 45

Signed by me at Chicago, county of Cook and State of Illinois, this 13th day of May, 1919.

HARRY H. IDE.
